(57) **CLAIM**

(21) Appl. No.: **29/111,948**

The ornamental design for an automotive T-shirt air freshener for attachment to rear view mirror, as shown and described.

(22) Filed: **Oct. 6, 1999**

DESCRIPTION

(51) LOC (7) Cl. **23-04**

FIG. 1 is a front top perspective view of an automobile T-shirt air freshener for attachment to rear view mirror showing my new design; and,
FIG. 2 is a rear perspective view thereof.

(52) U.S. Cl. **D23/367**

The broken line showing of environmental structure in FIGS. 1 and 2 is for illustrative purposes only and forms no part of the claimed design.
